DESIGN FOR A TABLE LAMP

Dorothy M. Simpson, Providence, R. I., assignor
to Electrical Testing Laboratories, New York,
N. Y., a corporation of New York

Application August 11, 1938, Serial No. 79,250

Term of patent 3½ years

To all whom it may concern:

Be it known that I, Dorothy M. Simpson, a citizen of the United States of America and a resident of Providence, in the county of Providence and State of Rhode Island, have invented a new, original, and ornamental Design for a Table Lamp, of which the following is a specification, reference being had to the accompanying drawing, forming a part thereof.

Figure 1 is a front elevation of a table lamp, showing my new design.

Figure 2 is a side elevation of the base and column thereof.

I claim:

The ornamental design for a table lamp, as shown.

DOROTHY M. SIMPSON.
